UNITED STATES PATENT OFFICE

158,743

FLOOR POLISHER OR THE LIKE

Lurelle V. A. Guild, Noroton Heights, Conn., assignor to Electrolux Corporation, Old Greenwich, Conn., a corporation of Delaware

Application October 26, 1949, Serial No. 5,723

Term of patent 14 years

(Cl. D9—2)

To all whom it may concern:

Be it known that I, Lurelle V. A. Guild, a citizen of the United States of America, residing in Noroton Heights, Connecticut, have invented a new, original, and ornamental Design for a Floor Polisher or the like, of which the following is a specification, reference being had to the accompanying drawing, forming part thereof.

Fig. 1 is a perspective view of a floor polisher or the like, showing my new design; and

Fig. 2 is a bottom view of the floor polisher shown in Fig. 1.

I claim:

The ornamental design for a floor polisher or the like, as shown.

LURELLE V. A. GUILD.
